(57) **CLAIM**

The ornamental design for a disposable bio-analysis cartridge, as shown and described.

DESCRIPTION

FIG. 1 is a left perspective view of the new design;

FIG. 2 is a right perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom plan view thereof.
